UNITED STATES PATENT OFFICE.

FRIEDRICH OTTO RUPPERT, OF CHEMNITZ, GERMANY.

MECHANICAL STOKER.

SPECIFICATION forming part of Letters Patent No. 508,985, dated November 21, 1893.

Application filed January 13, 1893. Serial No. 458,302. (No model.)

To all whom it may concern:

Be it known that I, FRIEDRICH OTTO RUPPERT, engineer, of 2 Platanenstrasse, Chemnitz, in the Kingdom of Saxony and German Empire, have invented a new or Improved Mechanical Stoker, of which the following is a specification, reference being had therein to the accompanying drawings.

This invention relates to apparatus for mechanically supplying coal or other fuel to boiler and other furnaces, and its object is to insure a regular and even distribution of the fuel. One form of the apparatus constructed to embody these improvements is shown in the accompanying drawings wherein—

Figure 1 illustrates a vertical section of the furnace and the stoking apparatus. Figs. 2 and 3 represent views at right angles to each other of the mechanism by which motion is imparted to the distributing shovel, and Fig. 4 shows the form of shovel adapted for use with furnaces or fire boxes, when the doors are narrower than the grates. Fig. 5 is a side elevation of the stoker, showing the means for operating the feed roller and shovel, applied to the stoker.

Referring to the drawings B is a hopper or receptacle containing the fuel which is to be introduced into the furnace. Next to it and between it and the furnace is the compartment A, containing the feeding roller g and the shovel b. The feeding roller g is formed or provided with suitable projections preferably in the form of ribs by means of which the fuel is fed forward upon the rotation of the roller. The shovel b consists of a suitable shaped bar or blade which is attached by means of the arms b' to the shaft a. The shape given to the shovel is such as to enable it to easily lift and carry the fuel.

The compartment A is provided with a door e which may be opened to give access to the furnace when it is desired to light the fire or should it ever be necessary to accomplish the stoking by hand. The same compartment is furnished with a door f through which the attendant may remove cinders or slags.

The firebox or furnace to which the apparatus is attached is indicated at c. It is preferred to mount the whole apparatus upon a frame or carriage furnished with wheels m.

To prevent the fuel being thrown about unnecessarily, as would happen if the shovel moved at an even speed a varying speed of 55 rotation is imparted to the shaft a to which the shovel is secured. This varying speed is obtained by providing the driving pulley s or its shaft a with a crank the pin of which i slides in a socket of a second crank, indicated 60 at h. This crank h is secured to the shaft a. It will thus be seen, that if the pulley s be rotated the shaft a is rotated with it and accomplishes a complete rotation at the same time, but its speed during the rotation varies 65 owing to the two shafts a and a not being in line. At the moment the shaft a attains its maximum of speed the fuel is discharged exactly from the shovel and thrown into the furnace.

Last but not least to insure an even distribution of the fuel upon the grate it is necessary that the maximum of speed, discharging the fuel, be made variable. For this purpose the shaft a is supported by a moving 75 slide or simply by a lever k, pivoted at β. An arm n is attached to the lever k. The other end of this arm is moved by a crank l, which is slowly rotated. The pin of this third crank may be adjustable. When the 80 lever k is oscillated by means of the crank l the distance between the two shafts a and a is altered continually, which has its effect upon the maximum of speed of the shaft a and shovel b so that the fuel may be thrown 85 alternately to any desired distance upon the grate.

The pivoting of β may be done over the shaft a or under it or to the left or right hand side.

If desired the crank l may be connected directly to the lever k by means of the socket o without the intervention of the arm n. The lever and arm may if desired occupy the position shown by the dotted lines k' and n'. 95

For driving the different shafts and rollers any suitable form of gearing may be employed.

Should the door or entrance to the firebox or furnace be of less width than the grate the form of shovel shown at b Fig. 4 may be adopted, by means of which the fuel diverges and is distributed over the full width of the furnace.

The operation of the apparatus is as follows: The fire having been lighted through the opening *e* the hopper *B* is filled with fuel and the feed roller *g*, the shaft *a* and the crank *l* are rotated by any suitable means. The fuel passes through the bottom of the hopper and is fed by the feed roller to the shovel *b* by which it is thrown upon the grate of the furnace.

10 This mechanical stoker may be fitted to every boiler without making change on the latter.

What I claim, and desire to secure by Letters Patent of the United States of America, 15 is—

1. In a mechanical stoker, the combination of the fuel chamber, a revolving shovel mounted in said chamber, a crank on the axis of the revolving shovel, and an eccentrically supported power shaft engaging the crank on the shovel axis, whereby the speed of the shovel can be accelerated for a portion of its revolution, as set forth.

2. In a mechanical stoker, the combination 25 of the fuel chamber, a revolving shovel mounted on a suitable axis and revolving in said chamber, a slotted crank on the shovel axis, an eccentrically mounted power shaft, and a crank-pin carried by said shaft and engaging 30 the slot in the shovel-crank, substantially as set forth.

3. In a mechanical stoker, the combination of the fuel chamber, a revolving shovel mounted on a suitable axis in said chamber, a crank on said shovel axis, a power shaft mounted 35 in movable bearings, and means of engagement between the power-shaft and shovel axis, substantially as and for the purpose set forth.

4. In a mechanical stoker, the combination 40 of the fuel chamber, a rotating shovel in said fuel chamber, a power shaft mounted in movable bearings, means of engagement between the shovel axis and the power-shaft, and means for automatically varying the position 45 of the movable bearings for varying the accelerated speed of the rotating shovel, as set forth.

5. In a mechanical stoker, the combination 50 of the fuel receptacle, the hinged door to said receptacle adapted to divide it into two compartments and afford means of access to the fire, a feed roller in the bottom of said receptacle, and a revolving shovel for throwing the coal onto the grate, substantially as set forth. 55

In witness whereof I have hereunto set my hand in the presence of two witnesses.

FRIEDRICH OTTO RUPPERT.
